GARMENT BUCKLE

Carl E. Anderson, Manasquan, N. J., assignor to
Eastern Tool & Mfg. Co., Belleville, N. J., a corporation of New Jersey

Application November 2, 1950, Serial No. 193,692

3 Claims. (Cl. 24—73)

1

This invention relates to garment buckles and more particularly to a buckle adapted to be secured to a flexible strap attached to one portion of a garment to secure the same to a second portion of the garment having a button secured thereto.

The device is particularly adapted for use in connection with garments such as workclothes, wherein the strap portions have marginal hems formed of a plurality of layers of the material stitched together. The hem portions of such straps are of substantially greater cross-sectional area than the strap proper. The buckle of the present invention is specially designed for use in connection with straps having thick marginal hems, the buckle being of such construction that the strap may be readily passed therethrough in the operation of securing the buckle to the strap. The buckle includes novel features of construction whereby the slot of the buckle, through which the strap is passed, may have a width substantially co-extensive with the greatest width of the buckle itself. The buckle of the present invention is further provided with novel means to engage the material of the strap to preclude slippage or displacement and with novel means to preclude excessive movement of the buckle parts in operation.

The buckle is further provided with novel means for registering the parts on closing the buckle to the position in which the same is attached to the strap, as will appear from the description below.

In the drawings:

Fig. 1 is a top plan view of a buckle embodying my invention,

Fig. 2 is a bottom plan view thereof,

Fig. 3 is a sectional view thereof, taken on line 3—3 of Fig. 2,

Fig. 4 is a sectional view taken on line 4—4 of Fig. 5,

Fig. 5 is a fragmentary plan view showing the buckle applied to a garment strap, and

Fig. 6 is a sectional view taken on line 6—6 of Fig. 2.

In the drawings, the buckle embodying the invention is designated by general reference character 10, the flexible garment strap to which the buckle is to be secured being indicated (Fig. 5) by reference character 11. The garment strap is formed, as shown in Fig. 4, by utilizing thicknesses of flexible material 31, 31' with marginal hems generally noted by reference characters 30, 30', stitched together, as indicated at 32, 32'. The buckle is utilized to connect the strap 11 with a button on the garment (not shown).

2

The buckle comprises a rectangular frame 12 having parallel top and bottom bar portions 13, 14, and connecting side bars 15, 16, defining an internal aperture 18. A plate 20 is provided with bearings 21, 21' engaging the top bar portion 13 of the frame to pivotally connect the plate to the frame and enable the lower edge 25 of the plate to be moved relative to the bottom bar portion 14 for a purpose presently explained. The plate is provided with side flange portions 22, 22' to telescopically overlie the outer edges of the side bars 15, 16 and register the plate therewith. These side flanges further serve as stop members engaging the side bars 15, 16 of the frame to preclude excessive pivotal movement of the plate 20 on the frame. The plate is provided with an elongated slot 23 which is substantially coextensive with the width of the internal aperture defined by the frame. The lugs 24, 24' extend substantially below the lower edge of the plate and define with the bottom bar portion of the frame, corner apertures 26, 26' disposed substantially inwardly of the ends of the slot 23 to receive the thick marginal hem portions 30, 30' of the strap when the buckle is secured to the strap. Lugs 24, 24' are provided with serrated edges 34, 34' to engage the material of the strap looped around the lugs, to preclude slippage and disengagement. A flange 27 extends below the lower edge 25 of the plate intermediate the lugs and is angularly bent relatively to the lugs to define therewith a space which is slightly greater than the cross-section of the lower bar of the frame. The parts are preferably made of relatively rigid material which is slightly yieldable under pressure.

In operation, the strap is passed through the slot 23 of the plate (Fig. 5) and looped around the lugs 24, 24' thereof and through the aperture 18 of the frame. Then pressure is applied to project the flange 27 (with the material of the strap looped around the same) over the bottom bar 14 of the frame.

The side flanges 22, 22' of the plate abut the side bars of the frame to register the parts and preclude excessive inner movement of the plate. The medial portions 31, 31' of the strap are gripped between flange 27 and bottom bar 14 of the frame tightly, as the primary gripping action of the device. Additionally, those portions of the strap immediately underlying the lugs 24, 24' will be held between said lugs and bottom bar 14 at a point opposite that at which the flange overlies the bar (Fig. 6) with the serrated edges 24, 24' of the lugs engaging the strap material. The parts are initially so proportioned that when the flange engages the bottom bar 14 of the frame,

the lugs 24, 24' will be spaced slightly from said bar, permitting the parts to allow for and accommodate themselves to the material of the strap which is tightly held therein, as above noted. The hem portions 30, 30' of the strap are engaged between the plate and bottom bar of the frame and are readily received in the corner apertures 26, 26', defined by the plate and bar, as above mentioned. Thus, it will be apparent that the operation of securing the buckle to the strap may be rapidly and conveniently performed. To disengage the buckle from the strap, the flange 27 may be forced out of its position of engagement with the bottom bar 14 of the frame; this requires application of force.

The frame is provided with a medially extended loop 17 or the like to receive a garment button for attachment of the strap thereto. It will be appreciated from the foregoing that the device may be readily and accurately manufactured at low cost and that its features of construction are such as to register the parts at all times, preclude accidental disengagement and enable the utilization of substantially the full width of the frame for the reception of the material of the strap.

Having thus described my invention, what I claim as new and desire to secure by Letters Patent is:

1. A buckle for attachment to a flexible garment strap having marginal edges of material stitched together in superposed relation in cross-section, said marginal edges defining hems of substantial cross-sectional thickness, said buckle being adapted to connect the strap with a button and comprising a rectangular frame having parallel top and bottom bar portions and connecting side bars defining an internal aperture, there being an upwardly extending button-engaging loop midway the length of the top bar, a plate, bearings on the plate engaging opposite end portions of the top bar portion to pivotally connect the plate to the frame, side flanges on the plate to telescopically overlie the side bars, register the plate therewith, and to preclude excessive pivotal movement of the plate, an elongated slot in said plate coextensive with the width of the internal aperture defined by the frame, lugs extended from the lower edge of the plate across the front surface of the bottom bar and defining therewith corner apertures disposed substantially inwardly of the ends of the slot to receive the thick marginal hems of the strap, said strap being passed forwardly through the slot in the plate and looped around the lower edge of the buckle plate and through the frame aperture and downwardly back of the bottom bar in use, and a flange extending below the lower edge of the plate intermediate the lugs, angularly bent rearwardly relative thereto, and defining therewith a space for receiving the lower bar of the frame, the parts being so proportioned that in closing the plate on the frame, the flange

of the plate may be snapped over the bottom bar of the frame with the strap therebetween and into tight engagement therewith, the side flanges of the plate being then in abutment with outer surface of the side bars of the frame, and the lugs being slightly spaced from the bottom of the bar, to accommodate the material of the strap.

2. In a buckle for attachment to a flexible garment strap as set forth in claim 1, the lugs having serrated edges to engage the strap material and the plate having flanges extending rearwardly along margins of the slot therein.

3. A buckle for attachment to a flexible garment strap having marginal edges of material stitched together in superposed relation in cross-section, said marginal edges defining hems of substantial cross-sectional thickness, said buckle being adapted to connect the strap with a button and comprising a rectangular frame having parallel top and bottom bar portions and connecting side bars defining an internal aperture, the top bar having a button engaging loop, a plate having hinge members pivotally connecting the plate and frame, an elongated slot in said plate coextensive with the width of the internal aperture defined by the frame, lugs extended downwardly from the lower edge of the plate in transverse spaced relation to each other and defining therewith and with the bottom bar corner apertures disposed substantially inwardly of the ends of the frame and under end portions of the plate to receive the thick marginal hems of the strap, said strap being looped around the lower edge of the buckle plate across lower ends of the lugs and having portions passed through the slot of the plate and through the frame aperture in use, and a flange extending below the lower edge of the plate intermediate the lugs, angularly bent relative thereto and defining therewith a space for receiving the lower bar of the frame, the parts being so proportioned that in closing the plate on the frame, the flange of the plate may be snapped rearwardly over the bottom bar of the frame with the strap therebetween and into tight engagement therewith, the side flanges of the plate being then in overlapping gripping engagement with the side bars of the frame, and the lugs and the flange between them being slightly spaced from the bottom bar of the frame, to accommodate the material of the strap.
